US0D1100324S

(12) United States Design Patent (10) Patent No.: US D1,100,324 S
(45) Date of Patent: * Oct. 28, 2025

(54) HAIR DRYER

(71) Applicant: Shenzhen Sunselection Technology Co., Ltd., Shenzhen (CN)

(72) Inventors: Shilin Liang, Shenzhen (CN); Xiu Sun, Shenzhen (CN); Boming Feng, Shenzhen (CN); Xinfeng Song, Shenzhen (CN)

(73) Assignee: Shenzhen Sunselection Technology Co., Ltd., Shenzhen (CN)

() Term: 15 Years

(21) Appl. No.: 29/802,880

(22) Filed: Aug. 9, 2021

(30) Foreign Application Priority Data

Feb. 9, 2021 (CN) 202130094086.X

(51) LOC (15) Cl. 28-03

(52) U.S. Cl.

USPC D28/13

(57) CLAIM

The ornamental design for a hair dryer, as shown and described.

DESCRIPTION

FIG. 1 is a perspective view of a hair dryer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines represent portions of the hair dryer that form no part of the claimed design.

1 Claim, 7 Drawing Sheets
